INVENTOR.

BY Samuel W. Denny

Thomas Denny
ATTORNEY.

Patented Feb. 14, 1928.

UNITED STATES PATENT OFFICE.

SAMUEL W. DENNY, OF DETROIT, MICHIGAN.

TOBACCO CONTAINER.

Application filed February 4, 1924. Serial No. 690,458.

My invention relates to a new and useful improvement in a tobacco container especially adapted for use in the packing and carrying of cigarettes and has for its object the provision of a cigarette box which will be simple in structure, economical of manufacture and highly efficient in use.

Another object of the invention is the provision of a cigarette container having a compartment for the carrying of matches and so constructed that the matches and cigarettes will be enclosed when desired and readily accessible as needed.

Another object of the invention is the provision of a container having a slideable container mounted in a shell whereby the contents of the container will be enclosed when the same is entirely within the shell and whereby the contents of the same will be available at a plurality of points when the container is moved to a predetermined position in the shell.

Another object of the invention is the provision of a cigarette container having means for projecting a cigarette therefrom.

Other objects will appear hereinafter.

The invention consists in the combination and arrangement of parts hereinafter described and claimed.

The invention will be best understood from a reference to the accompanying drawings which form a part of this specification and in which,

Fig. 1 is a perspective view of the container,

Fig. 2 is a perspective view of the outside shell showing the inside shell dotted in operative position,

Fig. 3 is a sectional view of the invention,

Fig. 4 is a perspective view of the modified form of the invention,

Fig. 5 is a perspective view of a further modified form of the invention,

Fig. 6 is a sectional view taken on substantially line 6—6 of Fig. 4, and,

Fig. 7 is a sectional view similar to Fig. 6 showing the gripping members in closed position,

Fig. 8 is a sectional fragmentary view of the bottom of the invention.

The invention, in its preferred form, comprises a shell or outside casing 10 having a transverse slot 11 formed in one side thereof. This shell or casing is adapted to receive the container 12 which is enclosed on

all sides and provided with a separate compartment having a base 13 and a side wall 14. Formed in one side of the container 12, is a transverse slot 15 which communicates with the separate compartment. A slot 16, which extends the full height of the separate compartment is also formed in one of the sides of the container. The slot 16 affords a means for filling the compartment with matches, and the slot 15 affords a means for removing the matches from the compartment. In this connection it is to be noted that the side walls of the container are cut away at the slot 15, to the depth of the slot. 70

Formed in the side wall of the container, extending the full height thereof, is a slot 17, through which the container 12 may be filled with cigarettes. Formed in the container 12, transversely thereof, is a slot 18, 75 which is positioned adjacent one end of the container, and through which the cigarettes in said container may be removed.

When the container is mounted slidably in the shell 10, the same may be slid relatively thereto. When the container is so positioned in the shell as to project slightly therefrom the cigarettes may then be removed from the container. The slot 15 will then be in registration with the slot 11, and thus the matches in the separate compartment will be accessible. 80

The container and the shell may be made from any desirable material, although it is preferred to have them made from metal. 90 The side walls of the container are provided with a projection which is angularly turned to form the keepers 29 and 30, providing channels in which may be positioned a piece of carborundum or other abrasive material 95 31 on which the matches may be struck.

In the form shown in Fig. 4 I have provided a container which is used separately from any shell. This container 19 is provided in one wall with an opening 20 through which a cigarette may be passed. This hole 20 is formed adjacent one end, and in the end wall there is formed an elongated slot 21 which terminates at one end in an enlarged slot 22 and at the other end in an 100 enlarged slot 23. Mounted slidably in these slots is a piece of resilient metal 24, doubled upon itself to form arms 25 and 26 which are arcuate and adapted to embrace a cigarette 28. The doubled over portion is pinned together by a suitable pin or rivet 27. When the gripping member is moved to the slot 23 105

the arms are spread apart, as shown in Fig. 6. When this member is moved along the slot to enter the restricted portion 21 the arms are brought together to grip a cigarette as shown in Fig. 7. The further movement of the gripping member will then project the cigarette through the opening 20, said gripping member being in alignment with said hole, the arms entering the slot 22 and releasing the cigarette.

In Fig. 5 I have shown a modified form of the invention whereby the box 29' is provided with an angularly extending side wall 30' having the gripping member mounted 15 in the apex thereof.

While I have illustrated and described the preferred forms of structure I do not wish to limit myself to the precise details of structure set forth but desire to avail myself 20 of such variations and modifications as come within the scope of the appended claims.

Having thus described my invention what I claim as new and desire to secure by Letters Patent is:

- 25 1. A container of the class described, comprising a shell having a slot formed in one of the side walls, adjacent one end; a container adapted for slidable movement in said shell, having a small and a large compartment, one of the side walls having a slot formed therein and communicating with the small compartment, said slot being a filling 30 slot and of a length equal to the height of said compartment communicated with, said side wall having a filling slot formed therein in communication with said large compartment, one of the other of the side walls of said container having a pair of slots formed therein, one communicating with each of said compartments, the one communicating with the small compartment being adapted for registration with the slot 35 in said shell upon slidable movement of said container relatively to said shell sufficient to expose the one communicating with the larger compartment, said filling slots being covered by said shell upon the registration 40 of said slots, as aforesaid.
- 45 2. A container of the class described, comprising a shell having a slot formed in one of the side walls adjacent one end; a container adapted for slidable movement in said shell, having a small and a large compartment, one of the side walls having a slot formed therein and communicating with the small compartment, said slot being a filling 50 slot and of a length equal to the height of said compartment communicated with, said side wall having a filling slot formed therein in communication with said large compartment, one of the other of the side walls of said container having a pair of slots formed therein, one communicating with each of said compartments, the one communicating with the small compartment being adapted for registration with the slot 55 in said shell upon slidable movement of said container relatively to said shell sufficient to expose the one communicating with the larger compartment, said filling slots being covered by said shell upon the registration 60 of said slots, as aforesaid.

5. A container having a pair of slots formed therein, one communicating with each of said compartments, the one communicating with the small compartment being adapted for registration with the slot in said shell upon slidable movement of said container relatively to said shell sufficient to expose the one communicating with the larger compartment, said filling slots being normally covered by said shell.

2. A container of the class described, comprising a shell having a slot formed in one of the side walls adjacent one end; a container adapted for slidable movement in said shell, having a small and a large compartment, one of the side walls having a slot formed therein and communicating with the small compartment, said slot being a filling 50 slot and of a length equal to the height of said compartment communicated with, said side wall having a filling slot formed therein in communication with said large compartment, one of the other of the side walls of said container having a pair of slots formed therein, one communicating with each of said compartments, the one communicating with the small compartment being adapted for registration with the slot 55 in said shell upon slidable movement of said container relatively to said shell sufficient to expose the one communicating with the larger compartment, said filling slots being covered by said shell upon the registration 60 of said slots, as aforesaid.

In testimony whereof I have signed the foregoing.

SAMUEL W. DENNY.
